UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

FLIER.

Application filed September 27, 1923. Serial No. 665,210.

To all whom it may concern:

Be it known that I, HJALMAR G. CARLSON, a citizen of the United States, residing at Worcester, in the county of Worcester and State of Massachusetts, have invented a new and useful Flier, of which the following is a specification.

This invention relates to a flier for use on a spinning machine. The principal object 10 of this invention is to provide a practical, convenient and economical construction of flier which can be made of die-pressed sheet metal and thus avoid turning and other machining processes that have been necessary 15 heretofore in the manufacture of these fliers. An especially important advantage lies in the fact that on account of the method of manufacture in dies, they always come alike and do not require the expensive balancing 20 heretofore necessary.

Another object of the invention is to provide the crown of the frame in such form that although made of die-pressed sheet metal, it will not have any cavities which 25 catch the air in rotating and cause whistling and other noises and also produce air resistance that retards the rotation and increases the power required as well as setting up vibrations.

Another object of the invention is to provide a hollow roving guide in such form that it can be made from a flat piece of sheet metal bent into circular form and will be provided in the operation of bending it with 30 a slit through it from end to end for receiving the roving in threading it and having the necessary irregularity for preventing accidental unthreading.

The invention also involves the manufacture 40 of the crown in such form that the roving guide, counterbalancing arm and central tubular bearing can be mounted accurately and in balance by inserting them through openings formed in the crown in the process 45 of manufacture and then securing them by simple brazing operations or in any other convenient way.

Other objects and advantages of the invention will appear hereinafter.

Reference is to be had to the accompanying drawings in which—

Fig. 1 is a front elevation of a part of a spinning frame showing a preferred form of

flier in position for winding the roving thereon;

Fig. 2 is an end view of the flier itself on enlarged scale without the bobbin or other features;

Fig. 3 is a front view of the same;

Fig. 4 is a sectional view of one of the 60 arms of the crown on the line 4—4 of Fig. 3, and

Fig. 5 is a transverse sectional view on the line 5—5 of Fig. 3 of the tubular roving guide to show the construction of the lugs 65 for locating the presser ring.

Fliers for the general purpose described have been made very expensively of forgings as a general thing. The necessity of securing delicate and accurate balance is well recognized in this industry and this is such a special art that men have to be employed for shaping and balancing the fliers who have spent a life time in that work. It has become a skilled art to such an extent that the 70 knowledge and skill is customarily handed down from father to son for generations. Obviously this renders the work very expensive.

They are made in very large quantities 80 and naturally many attempts have been made to manufacture them by methods that would be suitable for quantity production. Heretofore, however, success has not been obtained in minimizing hand labor although 85 numerous attempts have been made to form them in such a way that the proper balance will be assured mechanically without the necessity of filing them up here and there to get them into the proper balance. It has 90 been found also that in the attempts that have been made to make them of sheet metal, hollow spaces have been formed in them which entrap the air, greatly increase the air resistance and the power required to run 95 them, result in irregularities in their rotation and produce whistling noises that add to the confusion of the spinning room. Both the roving guide and the arm which balances it have had to be welded on the crown 100 in an expensive manner, one resulting in much inaccuracy; so that, after being welded, they have to be balanced up by those skilled in the art. It is difficult, with these sheet metal fliers that have been proposed 105 heretofore to accurately center the top bear-

ing cylinder. If that is not centered correctly, obviously the balance is all off, no matter how well the rest of the device is made. For the purpose of obviating these difficulties I make the flier in the following way.

In the first place, the center bearing stem or neck 10 is pressed out by sheet metal working processes into the form of a cylinder having a tapering inner passage. The top 11 of it is drawn in and centrally perforated so as to provide the proper supporting bearing to carry the flier on the spindle for the bobbin. The perforation is formed in 10 the die pressing operation and therefore is accurately made. This neck is provided with an opening 12 in the side for the usual purpose. Thus all necks can be cheaply and accurately reduplicated.

20 The crown 15 is formed solid by die-pressing operations not constituting a part of the present invention and in such a way that its upper surfaces are substantially flat except for a thread-guiding groove 16 which is formed thereon in the act of pressing one 25 arm of the crown. On the lower side the crown is preferably convex in cross section so that it may have stream line surfaces. Thus these edges will cut the air with a minimum of disturbance thereto and hence with 30 a minimum use of power to rotate the flier. Such stream line surfaces also reduce vibration and whistling to a minimum.

In the act of forming the crown it is provided with three cylinders 18, 19 and 20 all 35 integral with the arms of the crown and formed by die pressing operations. The central cylinder 19 constitutes a hub around the central bearing stem 10 and is formed of 40 such size and internal cylindrical shape as to just receive the stem 10, which is fitted into it and may be secured to it by any simple and easy means such as brazing or pinning.

45 The other two cylinders 18 and 20 also constitute hubs, the former receiving a rod 21 constituting the balance rod which may be formed of a solid piece of wire if desired. The other cylinder 20 is provided with a split perforation through it for receiving the 50 butt of the hollow roving guide 25. The rod 21 and the hollow guide 25 exactly fit the perforations in the two hubs 18 and 20 respectively without any finishing of either hub except that accomplished in the die 55 press. Each is fitted into its respective hub and brazed in position and thus they are permanently mounted. As these parts are all formed up in the dies, they come uniform and, the dies having been correctly designed for the product, the fliers as they are 60 assembled are found to be evenly balanced and substantially ready for application to the flier frame.

The roving guide 25 is formed from a 65 flat piece of metal cut out originally to such

form that at one edge it protrudes at 26 and the other edge has a complementary shape at 27. This piece of sheet metal is bent and formed into a cross section having a circular form so that these two edges, 70 which are smoothed previous to the bending operation, are brought nearly into contact with each other in the finished article. They furnish between them a threading slit 35 extending throughout the length of the guide, 75 and offset near the center for the usual purpose. The edges of this slit require but a minimum of hand finishing after the guide is made up and shaped into its final form. The guide is formed with a tapered passage 80 through it and its final form is, as usual, slightly tapering, having the general form of a cone.

In the flat blank from which the roving 85 guide is made, two projections 28 are formed near the center line of the blank and near one end. These two projections are of substantially the same thickness as the rest of the walls of the thread guide and have a passage 29 between them which is of uniform 90 width and smooth finish as produced by the dies. This groove receives the ring end 30 of the presser 31, the other end of which is provided with a circular socket, fitting on the end of the roving guide, and with the usual 95 pad.

Thus the presser may be permanently located and centered in position on the roving guide without the welding of any projections on the latter and without the necessity 100 of ordinary hand finishing operations, the parts being finished accurately enough in the dies and requiring only to be polished. The roving guide is comparatively light, does not have to be bored out through the center 105 and is of maximum strength. The whole device presents no surfaces that entrap the air to cause the whistling and other difficulties above mentioned. As the parts are formed cheaply and quickly in dies, are accurately finished thereby, are in true balance 110 when assembled and their production and assembly do not require expensive hand labor, therefore the cost of manufacture is greatly reduced under that heretofore incurred in this art. 115

Although I have illustrated and described only a single form of the invention I am aware of the fact that many modifications can be made therein by any person skilled in 120 the art without departing from the scope of the invention as expressed in the claims. Therefore, I do not wish to be limited to all the details of construction herein shown and described, but what I claim is:—

1. As an article of manufacture, a flier comprising a crown formed of a single piece of pressed solid metal having two diverging arms having a substantially stream line section and each terminating in an integral 130

hollow hub, one having secured therein a hollow pressed sheet metal roving guide and the other a balancing arm parallel with said guide.

5. 2. As an article of manufacture, a flier comprising a crown at the top formed of a single piece of die-pressed sheet metal having two diverging arms of a material thickness at their ends, each terminating in an 10 integral hollow hub, one for receiving the balancing arm and the other having secured therein a hollow roving guide parallel with said balancing arm.

15. 3. As an article of manufacture, a flier comprising a die-pressed crown having a central hub perforated centrally and provided with a die-pressed sheet metal bearing stem secured therein and having two integral arms projecting oppositely from the hub terminating in two integral cylindrical hubs 20 pressed from the metal of the arms, one having fixed therein a hollow roving guide adapted to support the presser arms and the other having a balancing bar secured 25 therein and extending therefrom parallel with the roving guide.

4. As an article of manufacture, a flier comprising a die pressed solid crown having a central hub perforated centrally and 30 provided with a die pressed sheet metal bearing stem extending therethrough and secured therein and having two integral arms projecting oppositely from the hub of convex shape in cross section on their inner surfaces and terminating in two integral 35 cylindrical hubs pressed from the metal of the arms, one having fixed therein a hollow roving guide adapted to support the presser and the other having a balancing bar secured 40 therein and extending therefrom parallel with the guide.

5. As an article of manufacture, a flier comprising a crown at the top formed of a single piece of pressed metal having two diverging arms having a cross section of a material thickness at its center and gradually tapering down at its opposite edges and each terminating in an integral hollow hub, one 45 for receiving the balancing arm and the other having secured therein a hollow roving guide parallel with said balancing arm, said guide being formed of a single piece of sheet metal bent into shape and having its

opposite edges of similar shape brought nearly in contact with each other to provide 55 a longitudinal slit between said edges through which the roving can be inserted, the hub having been split in line with said slit for that purpose.

6. As an article of manufacture, a flier 60 comprising a crown formed of a single piece of pressed metal having two diverging arms terminating in an integral hollow hub, one having secured therein the balancing arm and the other having secured therein a hollow 65 roving guide parallel with said balancing arm, said roving guide being formed of a single piece of sheet metal bent into shape and having its opposite edges brought nearly in contact with each other to provide 70 a longitudinal slit between said edges through which the roving can be inserted, one of said edges protruding and the other of a shape to substantially fit it and prevent the accidental disengagement of the 75 roving.

7. As an article of manufacture, a roving guide for a flier comprising a piece of sheet metal having its opposite edges of similar shape but one protruding and the other concave, said piece of metal being bent into circular form so as to bring its edges nearly together and form between them a longitudinal but off-set slit for receiving the roving in threading and preventing its accidental 85 unthreading.

8. As an article of manufacture, a roving guide for a flier consisting of a piece of sheet metal having its opposite edges of similar shape but complementary to each other, said 90 edges being brought nearly together so as to form between them a longitudinal but irregular slit for the roving and having near one end thereof a pair of integral hollow projections formed from the same piece of sheet 95 metal, spaced apart to form a support and guide for the ring of the presser.

9. As an article of manufacture, a flier having a crown the arms of which are flat in cross section on top and convex on the 100 bottom with thin edges for the purpose described.

In testimony whereof I have hereunto affixed my signature.

HJALMAR G. CARLSON.
